UNITED STATES PATENT OFFICE.

CHARLES E. KELLIHER, OF NEW YORK, N. Y.

POWER-DRIVEN SCISSORS FOR BARBERS.

Application filed August 12, 1927. Serial No. 212,454.

This invention relates generally to power driven scissors adapted for use by barbers, the invention having more particular reference to a novel type of power driven scissors which will act more efficiently.

The invention has for an object the provision of an improved power driven scissors of novel construction and arrangement of parts, embodying certain novel features.

For further comprehension of the invention, and of the objects and advantages thereof, reference will be had to the following description and accompanying drawings, and to the appended claims in which the various novel features of the invention are more particularly set forth.

Fig. 1 of the drawings, is a front elevational view of my improved power driven scissors.

Fig. 2 is a similar view, showing the cover removed so as to expose certain working parts.

Fig. 3 is a longitudinal sectional view taken on the line 3—3 of Fig. 2.

As heré embodied my improved power driven scissors comprises a case 10, having an extended handle element 11, of hollow construction, and having a cover 12 with a depending handle element 13, removably attached to the case 10, as at 14, by screws, bolts or the like. The handle cap 15, is provided with a flanged element 16, adapted to engage a recess 17, formed in the ends of the handle elements 11 and 13, and is removably attached thereto, by screws, bolts, or the like.

The tubular member 18, is rotatively mounted in the bearing 19 provided in the handle element 11, and has formed or cut in its lower extremity a notch 20, adapted to engage the extended element 21, of the driving member 22, attached to the flexible member 23, extended through an aperture formed in the end of the handle elements 11 and 13, and in the handle cap 15, the flexible member 23 has attached at its extended extremity, a suitable connection, as a means of connecting same to an electric motor, or any suitable prime mover, so as to rotate the tubular member 18, the latter described elements not being shown in the accompanying drawings.

The pinion 24 is attached to the tubular member 18 and meshes with a gear 25 attached to the jack shaft 26, so as to rotate the jack shaft 26. The pinion 27, and the gear 28 are attached to the jack shaft 26, rotatively mounted in the bearings 29 provided in the handle element 11, and are adapted

to be slidably engaged by the gear 30 and the pinion 31, respectively, attached to the tubular member 32, slidably mounted on the shaft 33, the tubular member 32 is provided with an inward depending member 34, a pin or the like, adapted to engage in an elongated slot 35 formed or cut in the shaft 33, so as to permit the said tubular member 32 to rotate the shaft 33. The above described construction being such as will permit the shaft 33 to be rotated at two different speeds.

The shaft 33 is rotatively mounted in the bearing 36 provided in the handle element 11, and is rotatively engaged in the tubular member 18. The lever 37 or trigger, is positioned outside the cover 12, and is attached to the screw 38, pivotally mounted in the cover 12, and has attached thereto a disc 39, provided with a pin 40, attached thereto, at or near its periphery, and extended therefrom, adapted to engage in an elongated aperture 41, formed or cut in the slidable member 42, provided with an elongated aperture 43, as a means of slidably attaching the slidable member 42, by the screw 44 to the inside of the cover 12. The leaf spring 45, is attached, at one extremity to the screw 44, and is provided with a bent free extremity, adapted to hold the slidable member 42 in any desired position. The slidable member 42 is provided with a fork shaped extremity 45 adapted to engage in the axial groove 46 formed or cut in the tubular member 32. The above described construction being such as will permit the lever 37 when pivoted to slide the tubular member 32 so as to rotate the shaft 33 at two different speeds.

The bevel pinion 47 is attached to the shaft 33, and meshes with a bevel gear 48, rotatively mounted on the pin 49, attached to the case 10. The lever 50, is attached to the bevel gear 48, and has pivotally attached at its free extremity, a link member 51, pivotally attached to the lever 52, pivotally attached to the pin 53, attached to the case 10. The movable scissor blade member 54, is pivotally attached to the pin 53, and is provided with a cutting edge 55, extended outside the case 10, and is provided with an extended element 56, located inside the case 10, having formed or cut therein a notch 57, adapted to receive the extended member 58 of the lever 52. The above described construction being such as will permit the bevel gear 48 when rotated to close the movable scissor blade member 54 in shear-

ing contact with the fixed scissor blade member 59, so as to cut hair, as may be desired. The fixed scissor blade member 59 is extended outside the case 10, and is provided with 5 a cutting edge 60, and is attached to the pin 53, and is provided with an extended element 61, located inside the case 10, and is attached as at 62, by a screw or the like to the case 10. The spring 63, is attached at one extremity 10 to the extended element 61 of the fixed scissor blade member 59, and is wound around the pin 53, and is attached, at its other extremity to the extended element 56 of the movable scissor blade member 54, so as to open the 15 said movable scissor blade member 54, when the bevel gear 48 is rotated, as is required when cutting hair.

The lever 64, or trigger, is positioned outside the cover 12, and is attached to the screw 20 65, pivotally mounted in the cover 12, and has attached thereto a pinion 66, located inside the cover 12, meshing with a pinion 67 attached to the lever 68, pivotally attached to the pin 69, and provided with an extended 25 element 70 located at its free extremity, adapted to engage in a notch 71 formed or cut in the extended element 56 of the movable scissor blade member 54, so as to limit the amount of opening of the movable scissor 30 blade member 54.

While I have above described the preferred form, construction, and arrangement of the several elements employed, it will be understood that the device is, nevertheless, susceptible of considerable modification therein, and I therefore reserve the privilege of resorting to all such changes as may be fairly embodied within the spirit and scope of the invention as claimed.

40 Having thus described my invention, what I claim as new and desire to protect by Letters Patent of the United States is as follows:

1. In a power driven scissors of the class described, adapted for use by barbers, a bevel

pinion attached to a shaft, said bevel pinion 45 meshing with a gear rotatively mounted on a pin, a lever attached to the said bevel gear, a link member pivotally attached to the free extremity of the said lever, said link member pivotally attached to a second lever pivotally 50 attached to a pin, a movable scissor blade member pivotally attached to the said pin, said movable scissor blade member provided with a cutting edge, and provided with an extended element having formed therein a 55 notch adapted to receive the extended member of the said second lever, so as to close the said movable scissor blade member in shearing contact with a fixed scissor blade member, as a means of cutting hair. 60

2. In a power driven scissors of the class described, adapted for use by barbers, a fixed scissor blade member provided with a cutting edge, said fixed scissor blade member attached to a pin, and provided with an extended element, a spring attached to the said extended element and wound around the said pin, and attached to the extended element of a movable scissor blade member, so as to open the said movable scissor blade member, said 65 spring working in co-operation with the pivoting of the said movable scissor blade member. 70

3. In a power driven scissors of the class described, adapted for use by barbers, a lever 75 attached to a screw pivotally mounted in a cover, a pinion attached thereto, and meshing with a second pinion attached to a lever, pivotally attached to a pin, said lever provided with an extended element located at its 80 free extremity, adapted to engage in a notch formed in the extended element of a movable scissor blade member so as to limit the amount of opening of the said movable scissor blade member. 85

In testimony whereof I have affixed my signature.

CHARLES E. KELLIHER.
